UNITED STATES PATENT OFFICE.

ELMER E. SARR, OF HURON, OHIO, ASSIGNOR OF ONE-HALF TO HARRY M. BONNETTI,
OF HURON, OHIO.

RAILWAY-CROSSING GATE.

Application filed December 9, 1924. Serial No. 754,816.

This invention relates to improvements in railway crossing gates.

The primary object of this invention is the provision of an improved gate structure adapted to be used at grade crossings, for the purpose of safe-guarding traffic, and which operates on a novel fluid pressure system, including details which render such a system valuable and of practical merit.

10 A further object of this invention is the provision of an improved railway crossing gate, of such a nature that the same will readily break upon collision of a vehicle with the same when in its closed position, and in such manner that inconsequential damage will only result to the gate and vehicle.

20 A further object of this invention is the provision of improved signal apparatus for use in connection with railway crossing gates, and novel means to operate the same.

25 A further object of this invention is the provision of improved fluid pressure operating means for crossing gates, and novel cut-out and release means therefor.

Other objects and advantages of this invention will be apparent during the course of the following detailed description.

30 In the accompanying drawings, forming a part of this specification, and wherein similar reference characters designate corresponding parts throughout the several views,

35 Figure 1 is a front elevation of the improved railway crossing gate, showing the same in an open position spanning a highway at a side of a railway crossing.

40 Figure 2 is a fragmentary cross sectional view taken through supporting and operating details of the improved gate structure.

Fig. 3 is a cross sectional view taken through the gate structure substantially on the line 3—3 of Figure 2.

45 Figure 4 is a plan view of a novel type of connection for the sections of the improved gate.

Figure 5 is a side view of the detail illustrated in Figure 4.

50 Figure 6 is a sectional view taken through the improved gate supporting structure, showing the gate in relation thereto.

Figures 7 and 8 are fragmentary sectional views taken through a circuit maker and breaker arrangement for a semaphore

adapted to be used in connection with gate 55 operation to warn engineers of the successful operation of the gate.

Figures 9, 10, 11, 12 and 13 are views illustrating details of a novel type of circuit maker and breaker arrangement for controlling signals adapted to warn traffic approaching the gate crossing.

Figure 14 is a sectional view designating the cooperative relation of a novel type of pressure operated cut-out switch and release 65 valve to be used in connection with the gate operation.

Figure 15 is a side elevation of the pressure operated switch illustrated in Figure 14.

Figure 16 is a side elevation of the improved pressure release valve illustrated in Figure 14.

Figure 17 is a cross sectional view taken substantially on the line 17—17 of Figure 14.

In the drawings, wherein for the purpose of illustration is shown only a preferred embodiment of the invention, the letter A may generally designate the improved grade crossing gate construction, which may include the gate B; means C for supporting the same; pneumatic operating means D; engineer signal apparatus E; and highway traffic signal structure F.

The gate B is preferably of the vertical sliding type, adapted to extend transversely 85 across the highway 20 when the gate is closed, and when open adapted to be suspended upwardly above the highway to permit the highway traffic to cross the tracks 21 which extend the highway at grade. The 90 gate B preferably is formed of structural steel or iron, and includes the sections 23 and 24, which are connected by easily severed means 25 at the center of the gate. The sections 23 and 24 when united to provide the gate B provide the top rail 26 formed of spaced angles extending in parallel relation; and the bottom rail 27 formed of spaced angles extending in parallel relation. It is to be understood that the rails 26 and 27 include parts for each of the sections 23 and 24, which are held together by means 25 to be subsequently described. The rails 26 and 27 are connected in their parallel relation by means of diagonal braces or struts 29, and the gate includes the vertical side angles 30 which at their lower ends extend below the rail 27 and are provided with diagonal braces

75

95

100

105

33 extending for connection to the rail 27, as is illustrated in Figure 1 of the drawings. The means 25, as is illustrated in Figures 1, 4 and 5 of the drawings, is provided for each 5 of the top and bottom rails 26 and 27, and it includes a plate 34 attached to each of the top and bottom rail portions of the section 24, and a pair of plate members 35 and 36, riveted or otherwise attached to each of the 10 top and bottom rails 26 and 27 of the gate structure 23, and providing pockets 37 at the ends thereof into which the ends of the plate 34 extend, as is illustrated in Figure 5 of the drawings. At the inside of the gate B, each 15 plate 34 is connected in the pockets 37 of the plate arrangement formed by plates 35 and 36, by means of a hinged pin 39. At the outer side of the gate B, the ear or corner 40 of each plate 34 is provided with a slot, 20 which receives the pin 41 therein; the pin 41 being carried by the outside corner of the plates 35 and 36. If a vehicle should hit the gate B, when closed, the force of the collision would be applied to the pins 39, 25 shear the same, and the gate sections 23 and 24 would then pivot on the pins 41, which would slide out of the slots in the ears 40 of the plates 34, and the gate sections 23 and 24 would then pivotally swing 30 in an open relation, and preventing excessive damage in such a collision.

Referring to the gate supporting means C, the same preferably includes base plates 43 and 44 bolted or otherwise secured on a top 35 of foundations 45 and 46 respectively, at each side of the highway 20. The plates 43 and 44 are each preferably provided with an upstanding annular projection 46^a, formed with an annular attaching flange 47 therefor. The attaching flange 47 is adapted to receive bolts 48 therethrough as a means of connecting the sockets 49 thereon. Between the sockets 49 and the flange 47 of each of the plates 43 and 44 gaskets may be 45 provided to make a leak-proof joint. The sockets 49 provide an interior screw threaded opening 50^a adapted to threadably receive the lower end of the tubular posts 50 and 51 which are respectively received by the plates 50 43 and 44 at the opposite sides of the highway 20. The supporting posts 50 and 51 may be of approved metal, and provide passageways 51^a therein adapted to receive sliding piston-weight arrangements of the pneumatic operating means D to be subsequently 55 described. The posts 50 and 51 at their upper ends are each provided with a detachable cap 55, having the upstanding spaced attaching lugs 56 integral therewith. The posts 50 and 51 are each reinforced and supported in vertical position by analogous bracing structures, and which bracing structures provide the main supporting structure for the gate B. Adjacent each of 60 the posts 50 and 51, upon the plates 43 and

44, the diagonally upwardly extending supporting structure 58 is provided, which consists of a pair of side angles 59 and 60 connected by the intermediate diagonal cross brace means 61, in a converging relation 70 from the base plates 43 and 44 upwardly toward the upper ends of the supporting posts 50 and 51. At their lower ends each of the structures 58 is securely connected with the foundation plate by means of angles 63 and 64, which are illustrated in various figures of the drawings, and extend from the base of the diagonal supporting structures 58 for connection to the annular upstanding parts 46^a of the said base plates. At their upper ends the supporting structures 58 are connected to the spaced attaching lugs 56 by means of a pair of spaced plates 67 and 68; said plates 67 and 68 providing a casing or compartment therebetween within which is rotatably supported a sheave or pulley 70, upon a pin 71, so that the periphery of the pulley 70, which is grooved, is tangential with the axis of the respective post 50 or 51 adjacent which it is positioned. Over the top of the compartment between the plates 67 and 68, a closure 73 is provided, hinged at 74 adjacent the top of the structures 58 and at its free end extending downwardly about the pulley 70 in spaced relation therewith to provide protection therefor. The structures 58 at the sides of the highway 20 are upwardly connected by means of a top cross brace 75, which may be a pair of angles bolted not only to the tops of the side supporting structures 58, but also being bolted to the attaching lugs 56 at the top of each of the posts 50 and 51, and as is illustrated in Figures 2 and 3 of the drawings.

In each of the foundations 45 and 46 it is preferred to provide a compartment 76, in which a drain tank is positioned, connected with the interior of cylinders or tubes 50 and 51 by means of conduits 77, so that water, moisture, and the like may drain from the passageways 51, over the downwardly sloping floors 78 and into the conduits 77, and then into the drain tanks 77^a. Suitable exit conduits 79 are provided for each of the tanks 77^a, so that the water may drain from the tanks 77^a, or may be withdrawn; a valve 80^a being preferably provided in each of the conduits 79.

Referring to the means D for elevating the improved gate B, it is to be noted that the gate structure B is laterally provided with groove wheels 80 and 81 supported on shafts 83 and 84 respectively; said shafts being supported by means of laterally extending flanges or members 85 so that the grooves of said wheels may receive the post 50 in sliding engagement therein. At the opposite side of the gate, wheels 87 and 88 are similarly provided, being supported on 125

pins 89 and 90 respectively. Guide straps 91 and 92 are carried at the left side of the gate extending about the tube or cylindrical post 50, and in similar manner guide straps 93 and 94 are provided at the opposite side of the gate B for the vertical post or cylinder 51. These guide straps prevent the detachment of the sections 23 and 24 from the posts or cylinders 50 and 51, should the 5 gate be broken at its center by means of collision, as above suggested. The gate B is supported at its ends by means of cables 95 and 96 trained upwardly over the pulleys 70; said cables respectively extending down 10 through the caps 55 of the cylindrical shaped posts 50 and 51, and within said posts 50 and 51 being attached to suitable piston-weight structures 97.

Referring to the structure 97 the same 20 preferably includes a rod 98, which at the upper end thereof detachably supports a stop swivel 99, to which the cable 95 or 96 is connected. The rod 98 of course extends downwardly through the passageway 51^a, 25 and at the lower end thereof detachably supports a piston 100. At the lower surface of the piston a gasket 101 is clamped by means of a spider 102 which is attached to the piston 100, so that the gasket or packing 101 is 30 forced into engagement with the walls of the tubes 50 or 51, in order to provide a piston arrangement. Upwardly of the piston 100 a series of removable weights 103 are supported, in any desired number, as a means 35 of counterbalancing the weight of the gate B. The total weight of the weights acting on the cables 95 and 96 is sufficient to elevate the gate B when atmospheric pressure exists in the passageways 51^a of the tubes 50 40 and 51.

Referring to the operating means D, the same includes a pump 107, which is operated by means of a motor 108, for the purpose of supplying air under pressure to the cylindrical shaped tubes 50 and 51, to operate beneath the pistons therein. Connected with the pump 107 is a conduit 109 which has communication with the lower portions of each of the posts 50 and 51, as a means of 45 supplying air pressure to said posts for coaction with the piston arrangements. The motor 108 is adapted to be operated by means of a circuit 110, which has a storage battery 111 therein, and this circuit 110 includes a switch 112, which is automatically operated at a desired point by the passing 50 of a train over the rails, as the train is approaching the grade crossing, and in accordance with any conventional structure 55 well known to those skilled in the art to which this invention relates. It will of course be understood that upon building up the air pressure incident to operation of the pump 107, the air pressure in the cylinders 60 or tubes 50 and 51, beneath the piston struc-

tures 97 therein, will force the piston structures upwardly in their respective cylinders, and the gate B incident to its weight will drop into a closed position across the highway 20.

The operating means D in order to render the same practical also includes the pressure cut-out mechanism 115; and the pressure release mechanism 116.

Referring specifically to the pressure operated switch mechanism 115 for controlling the circuit 110, the same is provided in order to insure that the motor will not operate the pump 107, after the desired pressure has been obtained. It has been found that a maximum of 15 pounds per square inch superatmospheric pressure should not be exceeded. The structure 115 includes the body portion 118, provided with a base 119; laterally extending attaching flanges 120; and the vertical switch attaching plate 121. The base 119 is centrally provided with the tubular extension 123, and a lateral branch 124 from the conduit 109 is adapted to be connected to this extension 123 by nut means 125, so that the air pressure from the pump conduit 109 may pass through the way 126 into the chamber 127 provided by the body 118. A piston 128 is slidably mounted in the chamber 127, and includes a rod 129 which extends vertically upward through the body 118, and through a packing nut 130 at the top of the body 118. A spring 131 is disposed within the chamber 127, at one end engaging the nut 130, and at the other end engaging the piston 128 to normally force the latter downwardly in the chamber 127, against the detachable base plate 119.

At its upper end the piston rod 129 extends exteriorly of the body 118, through the nut 130, and is connected with a switch mechanism 132, for the purpose of operating the same. This switch mechanism 132 is located in the circuit 110, and it includes the plate 133 of insulating material, upon which the laterally extending insulation tracks 134 and 135 are provided, in spaced relation. At their facing surfaces these tracks 134 and 135 have contact strips 136 and 137 respectively, in spaced facing relation, and with which contact strips 136 and 137 terminal binding screws 139 and 140 are respectively connected, as a means for attaching the wires in the circuit 110. In the space between the tracks 134 and 135 it is preferred to provide a supporting stem 141, which at an end is detachably connected with the piston stem 129, and which between the tracks 134 and 135 supports resilient contact arms 144 and 145 in respective engagement at their free ends with the contacts 136 and 137.

Referring to the operation of the switch cut-out structure 115, when the pressure in the operating piston exceeds 15 pounds superatmospheric pressure, the said pressure

will overbalance the action of the spring 131, force the piston 128 upwardly in the chamber 127. This will move the contact supporting rod 141 and the contacts 144 and 145 therewith, so that said contacts 144 and 145 will ride off their respective contacts 136 and 137, and thus break the circuit 110, when the maximum pressure has been exceeded. This circuit maker and breaker construction 10 115 thus prevents injury to the operating system D, and insures the effective operation of the gate in maintaining the same lowered notwithstanding the fact that the circuit 110 has been broken, so long as the proper super- 15 atmospheric pressure exists on the pistons. Of course, if the pressure on the pistons falls below a predetermined amount the spring 131 will return the switch contacts to close the circuit 110, should the train still be on 20 the trackway so as to maintain the automatic switch 112 closed in the circuit 110.

Referring to the circuit release valve 116, the same includes a supporting body structure somewhat similar to the body structure 25 of the controlling switch structure 115 above mentioned, and preferably provides the receptacle body portion 150 having a chamber 151 therein within which a piston 152 slides. The body 150 supports a detachable 30 base plate 153 therein which has a vent duct 154 therein. The piston 152 preferably includes a pair of spaced plates 155 and 156, connected in a fixed relation by a hub 157, so that the space between said piston plates 35 155 and 156 is normally in alignment with a lateral duct 158 with which the conduit 109 communicates, so that the air pressure normally acts in the space between the plates 155 and 156, preventing escape of air pressure. A piston rod 160 is provided for the 40 piston 152, extending upwardly through a packing nut 161, and the spring 162 normally forces the piston 152 into the position above mentioned with respect to the exit conduit 158. Externally of the body 150, the 45 stem 160 of the piston supports a core 164, operating in the passageway of a solenoid 165; this solenoid being supported in a casting 166 carried at the upper end 167 of the body of the device 116. The solenoid 165 is energized by means of the closing of a circuit by the train operating on the tracks 21 after the train has passed the grade crossing a sufficient distance. The closing of such 50 circuit (not shown) will energize the solenoid 165, so that the core 164 is drawn upwardly therein, and against tension of the spring 162 the piston 153 is lifted to uncover the duct 158, and permit the escape of 55 air pressure from the conduit 109 through the vent opening 154. The body structure 60 of the device 116 may have attaching flanges 168.

Referring to the engineer's signal arrangement E, the same includes a semaphore arm

170 which is pivotally supported between the ends by means of a shaft 171 supported by a switch box 172; the latter being preferably attached to the supporting structures 58 at a side of the gate. The arm 170, as is illustrated in Figure 3 of the drawings, at one end thereof is provided with the disc 172^a, appropriately colored to signal to the engineer, and at the other end is provided with a counterweight 173 sufficient to return the arm to an inoperative vertical position, as is illustrated in Figure 1 of the drawings. The arm 170 adjacent the disc 172^a is provided with a signal lamp 174, which as is illustrated in Figure 7 of the drawings, is disposed in a circuit 175. This circuit has a novel switching device 177 within the switch box 172, which consists of an insulated drum 178^a movable with the shaft 171. The drum 178^a has a pair of spaced 85 relatively insulated contacts 178 and 179 therein, which are adapted to respectively contact with terminal contacts 180 and 181; the latter contacts being carried by a stationary portion 182 in the switch box 172, and as is illustrated in Figure 7 of the drawings. The contacts 180 and 181 are relatively insulated on the support 182, and are connected in a portion of the circuit 175, wherein a storage battery 184 is provided. As the arm 170 swings to a horizontal position for signalling purposes, the contacts 178 and 179 will bridge and engage the terminal contacts 180 and 181 respectively, closing the circuit 175 and illuminating the lamp 174 for signalling purposes. Of course, the arm 170 operates transversely of the gate, and extends outwardly over the trackway 21 to signal to the engineer of the approaching train that the gate is closing. As to the movement of the arm 170 to an operative position, this is effected by the lowering of the gate B. The gate B as it moves to a closed position engages a lever 186, which is pivotally connected to a shaft 187 mounted over the base 43, preferably in the connecting angles 63 and 64, and as is illustrated in the drawings. This shaft 187 moves with the lever 186, and at the opposite side of said shaft from the lever 186 a lever 188 is connected therewith, and which lever 188 in turn connects with the semaphore arm 170 by means of a connecting rod 189. Therefore, as the gate lowers to engage the lever 186 as is illustrated in Figure 2 of the drawings, the shaft 187 will be moved to move the lever 188 into the position illustrated, which will move the connecting rod 189 outwardly, and swing the semaphore arm 170 into a horizontal position. This operates the signal lamp 174 as above described, counterweight lever 189 returns lever 186 to the position illustrated in Figure 1.

Referring to the signalling mechanism F

which is adapted to be used in connection with the warning of traffic traveling on the highway 20, the same preferably includes a siren 200 which is carried on the top of the gate B, and a "Stop" signal 201 which is carried by the gate B; the latter including portions 202 and 203 which are carried by the gate sections 23 and 24 respectively, and which may separate when said gate sections are broken apart. The "Stop" signal 10 includes a lamp 204, operating in a circuit 205, and the siren 200 operates in a circuit 206. The circuits 205 and 206 receive their current from a storage battery 207, and this 15 storage battery 207 is preferably connected at one pole thereof to the vertically disposed control member 208 which is carried longitudinally adjacent the tube or cylinder 50, as is illustrated in the drawings. This 20 member 208 is in the form of an angle in cross section, and includes the legs 209 and 210. A switch box 211 is carried by the gate B, and within this switch box 211 relatively insulated contacts 212 and 213 are 25 placed, connected respectively in the circuits 205 and 206. A supporting arm 214 extends laterally from the gate B, and oscillatively supports a shaft 215 therein, which extends into the switch box 211, and therein 30 is provided with a right angled arm 216 which supports laminated brushes 217 and 218 for respective cooperation with the contacts 212 and 213. At its opposite end exteriorly of the switch box 211 the shaft 215 35 supports a right angled arm 219, which at the free end thereof pivotally supports an operating lever 220, on a pin 221, between the ends of said lever 220. The lever 220 is mounted for pivotal movement in a vertical plane transversely of the vertical plane 40 in which the arm 219 moves as the shaft 215 is oscillated, and this lever 220 at the inner end thereof is provided with a counter weight 223, normally urging the lever 220 into a horizontal position against a stop 45 224 of the arm 219. The lever 220 at the end opposite the counter weight 223 is provided with a detachable fixed pin 225, upon which is rotatably mounted a grooved roller 50 226, adapted to operate over the serrated edge of the leg 210 of the member 208, as will be subsequently described. The plane of revolution of this wheel 226 is at right angles to the axis of the lever 220, and the 55 pin 225 outwardly of the roller 226 is provided with an extension 229, which itself supports a pin 230 in right angled relation, and upon which pin 230 a side roller 231 is mounted for revolution in a plane at 60 right angles to the roller 226.

At the serrated edge of the leg 210 of the signal operating member 208, a plurality of projections 235 are provided, at the upper portion thereof, over which the roller 226 is adapted to roll in its travel along the mem- 65 ber 208, as the gate B is descending. In its normal position the lever 220 bears with its weight against the member 208, incident to the inclined position of the arm 219. The roller 226 will therefore follow the 70 edge of the leg 210, as is apparent, and as the roller 226 rolls over the projections 235, both the brushes 217 and 218 will engage their respective contacts for operating the lamp 204 and the siren 200. 75 This occurs during the initial part of the descent of the gate B, and the circuits of both the lamp and siren will be broken when the roller 226 rolls into the depressions between the projecting portions 235, and as 80 will be apparent from the drawings. As the gate B is moving to its finally closed position, it is to be noted that the roller 226 will roll over projections 238 which are shallower than the projections 235, so that when roller 226 engages these projections 238 the arm 216 will only be rocked to the position illustrated in Figure 13 of the drawings, so that the brush 217 will engage the contacts 212 85 for operating the signal lamp 204, but the brush 218 will not be in a position to engage its contact 213, so that the circuit 206 will be inoperative and the siren will not sound. The signal lamp 204 therefore continues to 90 flash intermittently during the descent of the gate B, so long as the roller 226 rides over the projections 235 and 238. When the gate B has reached its closed position, the roller 226 will have passed a depression 240 in the leg 210 of the member 208, as is illustrated 95 in Figure 3 of the drawings. On its upward ascent the gate B will of course carry the lever 220 therewith, in the horizontal position illustrated in Figure 9 of the drawings, but upon continued upward movement 100 of the gate B, the roller 226 will engage the shoulder 241 provided in the depression 240, and will hold the lever 220 in fixed position at the roller 226, rocking said lever 220 on its pivot pin 221, into the position illustrated by the dotted lines, and as the gates move upwardly the roller 231 at the extreme end of the lever 220 will have passed to the inside of the leg 210, and will engage said leg 105 210; the roller 226 during this movement being well out of engagement with respect to the serrated edge of the leg 210, so that the signal circuits 205 and 206 are maintained inoperative, since the brushes 217 and 218 110 will be lifted off their respective contacts in said circuits. As the gate B moves to its open position at the top of the supporting structure C, the rollers 231 will ride off the leg 210, passing through the opening 243, 115 illustrated in Figure 3 of the drawings, and the counterweight 223 will return the lever arm 220 to its normal horizontal position with the grooved roller 226 in position to engage the edge of the leg 210 when the gate 120 B again descends, so that the switch struc- 125

tures of the circuits 205 and 206 will be operated upon descent of the gate B, in the manner above described.

From the foregoing description of this invention it is apparent that a novel type of crossing gate has been provided, which embodies practical details which render the same of merit. The fluid pressure operating system is fool-proof, and a well stabilized pressure will be maintained at all times during operation of the gate. The warning apparatus for the engineer and traffic on the highway is of particular importance, and possesses novel features.

Various changes in the shape, size, and arrangement of parts may be made to the form of invention herein shown and described, without departing from the spirit of the invention or the scope of the claims.

I claim:

1. In a crossing gate of the class described the combination of a pair of tubular supporting posts, a gate, means slidably connecting the gate to the vertical supporting posts, piston means in the posts having connection with said gate, weight means in the posts connected with the piston means normally elevating the gate, and means for supplying fluid pressure to the piston means to counter act the weight means and lower the gate.

2. In a crossing gate the combination of a pair of vertically disposed cylinders at opposite sides of a roadway, a gate, roller means at the ends of the gate engaging said cylinders, piston means in said cylinders, cable means connecting said piston means with said gate, weight means acting on said piston means to elevate said gate, and fluid pressure means for supplying pressure to the cylinders for elevating said weight means and piston means in said cylinders and permit lowering of said gate.

3. In a crossing gate structure the combination of a gate, a pair of vertical cylinders, guide means connecting the ends of the gate to said cylinders with the gate therebetween, piston means operating in said cylinders, a supporting structure including pulleys over-head of said cylinders, cables connected with said piston means trained over said pulleys and connected with said gate at the ends thereof, weight means normally acting on said pistons in the cylinders to maintain the gate elevated incident thereto, and means for supplying air pressure to the cylinders below said pistons to elevate said weight means and pistons in the cylinders and lower said gate between said cylinders.

4. In a crossing gate the combination of

a supporting structure, vertical cylinders, sheaves carried by the supporting structure over said cylinders, a gate slidably connected with said cylinders for vertical movement therebetween, cables connected to said gate at the ends thereof and trained over said sheaves and extending into said cylinders, pistons in said cylinders connected to said cables, weights on said pistons, operating means for supplying fluid pressure to the cylinders to operate said pistons and elevate the same and said weights to lower said gate, means to release said fluid pressure at a predetermined time and permit said weights to elevate said gate, and means for maintaining a substantially constant fluid pressure in said cylinders.

5. In a crossing gate the combination of a pair of supporting cylinders vertically arranged, a gate slidable in vertical manner between said supporting cylinders, pistons in said supporting cylinders, cable means connected with said pistons and with said gate, weight means carried by said pistons for elevating the gate and lowering the pistons in said cylinders, a pump, conduit means connecting the pump with the lower portions of said cylinders for supplying air pressure into said cylinders for acting on said pistons to lift said weights and permit lowering of the gate by its weight, motor means for operating said pump, and means for releasing air pressure from said cylinders.

6. In a gate construction the combination of a gate body comprising a pair of sections, means movably mounting said sections at their outer ends to permit vertical movement of the gate to elevate the same, means mounting the sections at their proximate ends for pivotal movement whereby the sections may give with respect to each other, and become detached with respect to each other, and easily severed holding pins normally connecting the gate sections in a rigid relation at their proximate ends.

7. In combination a supporting structure, a gate, means normally maintaining the gate elevated at said supporting structure, means to lower the gate, a pivotally mounted semaphore arm normally maintained in an inoperative position, a pivotally mounted lever at the lower portion of the supporting structure, connecting means between the pivotally mounted lever and the pivotally mounted semaphore arm, said gate when lowered into closing position being adapted to engage said pivotally mounted lever to actuate the semaphore arm into an operative position.

ELMER E. SARR.

CERTIFICATE OF CORRECTION.

Patent No. 1,646,877.

Granted October 25, 1927, to

ELMER E. SARR.

It is hereby certified that the name of the assignee in the above numbered patent was erroneously written and printed as "Harry M. Bonnetti", whereas said name should have been written and printed as "Harry M. Bonnette", as shown by the records of assignments in this office; and that the said Letters Patent should be read with this correction therein that the same may conform to the record of the case in the Patent Office.

Signed and sealed this 22nd day of November, A. D. 1927.

Seal.

M. J. Moore,
Acting Commissioner of Patents.
